ABSTRACT OF THE DISCLOSURE

Apparatus is described for expediting the removal of protective waxed paper from a band of cellophane tape surrounding and extending inwardly of an aperture in a punched card preparatory to mounting a microfilm in the aperture by means of the tape. When the card is received in a slot, the aperture in the card lies in register with an aperture in the bottom of the slot with a portion of the waxed paper overlapping a separating edge. When the card is fully inserted, a limit switch is closed to energize a solenoid which punches the waxed paper free of the cellophane tape and beneath the separating edge where it remains trapped. When the card is then removed with a normal pulling motion, the waxed paper is separated from the tape by means of the separating edge without damage to the tape; and the separated waxed paper falls into a convenience receptacle.

BACKGROUND AND SUMMARY

The present invention relates to apparatus for removing the protective waxed paper from a band of cellophane tape surrounding and extending inwardly of an aperture in a punched card. The waxed paper must be removed preparatory to mounting a microfilm in the aperture by means of the tape.

Heretofore, for low production volumes, the waxed paper was normally removed by hand; and the microfilm was mounted accurately within the aperture by means of a separate machine. For very large production volumes, machines have been built for automatically removing the protective waxed paper and mounting the microfilm in proper position without the need for handling by an operator. Such machines, however, are expensive; and there has been found to be a need for handling the cards on an intermediate production volume.

The present invention provides a simple and economical machine wherein an operator may accomplish the step of removing the protective waxed paper efficiently and rapidly in comparison with the hand-removal operation. Further, it has been found that the incidence of damage to the cellophane tape is greatly reduced by means of the operation of the present invention—thus, not only saving time, but also producing a significant saving in materials.

Other features and advantages of the present invention will be apparent to persons skilled in the art from the following detailed description of a preferred embodiment accompanied by the attached drawing wherein identical reference numerals will refer to like parts in the various views.

THE DRAWING

FIG. 1 is a perspective view of a completed apparatus according to the present invention;

FIG. 2 is a plan view of a punched card prior to insertion in the apparatus of FIG. 1;

FIGS. 3-4 are detailed views of the plunger head;

FIG. 5 illustrates the operation of the apparatus of FIG. 1 upon insertion of a punched card; and

FIG. 6 is a simplified circuit schematic of the device of FIG. 1.

2

DETAILED DESCRIPTION

Turning now to FIG. 1, there is seen in perspective view, a device constructed according to the present invention. The device includes a lower housing or base generally designated 10 which receives a drawer or receptacle 11 for collecting the removed waxed papers. To the top of the housing 10 there is mounted a thin sheet of plastic material 12 having an upwardly turned forward edge 13; and the plastic member 12 is spaced slightly above the top of the housing 10 to define a slot 14 which receives a punched card shown in chain line in FIG. 1 and identified by reference numeral 15. The plastic member 12 defines an aperture 17 which is located directly above a corresponding aperture 18 in the top of the housing 10.

Mounted to the sides of the housing 10 and extending above the apertures 17 and 18 is an inverted U-shaped bridge 20, on the top of which is mounted a latching solenoid 21. The latching solenoid 21 includes a coil 22 and a plunger 23. The plunger 23 extends entirely through the solenoid 21, and at its lower end is provided with a punch member 25 (seen in greater detail in FIGS. 3 and 4) which has a lower inclined surface 26 located so as to project through the apertures 17 and 18 when the solenoid 21 is energized.

Located at the rear (i.e. the far end as seen in FIG. 1) of the slot 14 and mounted to the back of the housing 10 is a limit switch equipped with a movable armature 30 which is engaged by the punched card 15 when fully inserted. When the limit switch 30 is engaged by the inserted punched card, it energizes the solenoid 21 to force the punch member through the apertures 17 and 18. The armature of solenoid 21 may be spring-loaded to return to its top position when switch 30 opens, or it may be de-energized upon completion of a full stroke so that the armature will return to its rest position until the solenoid is again energized.

A typical punched card for use with the present invention is seen in FIG. 2 as comprising a card 33 having left hand portion including a plurality of conventional machine type punches 34 for identification and a rectangular or square aperture 35. Mounted about the top of the aperture 35 is a peripheral band of cellophane tape 37 which is secured to the face of the card and defines an inner peripheral band which extends slightly within the boundaries of the aperture 35. Mounted within the aperture 35 and beneath the peripheral band of cellophane tape 37 is a rectangular (or square) sheet of waxed paper 39, the borders of which are shown by the dashed line 40. When the card 33 is fully inserted, the position of the punch 25 is shown in FIG. 2 by means of the chain line identified by reference numeral 25'.

Turning now to FIG. 5, there is shown a detailed viewing of the action of the punch 25 to separate the waxed paper 39 from the peripheral band of cellophane tape 37. As shown therein, when the limit switch is energized (schematically represented by the switch 30a in FIG. 6 which is coupled in series with the coil 22a of solenoid 21 across a conventional source of supply) the punched member 25 is driven through a downward stroke to the chain line identified by reference numeral 25a thus separating a portion of the waxed paper from its associated portion of the cellophane tape 37.

It will be observed in FIG. 5 that when the card 33 is fully inserted, the forward portion of the aperture 18 (identified by reference numeral 45 in FIG. 5) extends beneath the waxed paper 39 so that when the plunger separates the waxed paper from the tape, it will first move to a position shown in chain line and identified by reference numeral 46 which is well below the lower surface of the housing 10; and (since it is resilient and still partially secured to the cellophane tape) it will then return to the

position shown in dashed line and identified by reference numeral 47 wherein the trailing edge of the waxed paper 39 will be trapped beneath the forward edge 45 of the aperture 18 in the housing 10. Thus, when the card 33 is removed (by pulling to the right in FIG. 5) the edge 45 acts as a separating edge to completely remove the waxed paper 39 from the peripheral band of the cellophane tape 37 whereafter the waxed paper drops into the drawer 11. In practice, it has been found useful to have the separating edge 45 slightly inclined toward the rear of the machine in proceeding from left to right in FIG. 1 so as to insure a trapping of the cellophane paper at the right hand portion of the aperture.

In operation, the insertion of the card and triggering of the limit switch 30 operates very much like the action of a time card printing mechanism—that is, a very steady, but not too quick, insertion will close the limit switch 30. The solenoid 21 is energized and it pushes the trailing edge of the waxed paper beneath the separating edge 45 of the housing 10 where it is trapped. By then removing the card with the same steadiness of action, the armature of the solenoid is returned and the waxed paper is completely separated from the peripheral band of tape. As has already been mentioned, it has proven to be highly reliable by greatly lowering the incidence of damage to the peripheral band of cellophane tape. The card may then be moved to a second machine for the separate mounting of the micro-film in place of the removed protective waxed paper.

Having thus described in detail a specific embodiment of my invention, it will be apparent to persons skilled in the art that certain modifications and substitutions may be made for the specific structure or circuit elements disclosed; and it is, therefore, intended that all such modifications and substitutions be covered as they are embraced within the spirit and scope of the appended claims.

I claim:

1. Apparatus for removing a sheet of protective waxed paper held in an aperture of a card by means of a peripheral band of cellophane tape, comprising: support means providing a surface for receiving said card in supporting position with said waxed paper on the underside of said tape, said supporting surface defining an aperture partially limited by a separating edge extending beneath said

waxed paper when said card is received in a predetermined position on said surface; solenoid means including a plunger defining a lower surface mounted in a first position above said aperture adjacent said separating edge and adapted for movement to a second position beneath said supporting surface for punching a portion of said waxed paper through said aperture when said solenoid means is energized; and limit switch means responsive to the placement of said card at said predetermined position for energizing said solenoid, whereby said lower surface of said solenoid plunger will engage the waxed paper, separate it from said peripheral band of tape, and force it beneath said separating edge to trap the separated portion of said waxed paper beneath said supporting surface when said solenoid returns whereupon removal of the card will draw said waxed paper over said separating edge to completely separate waxed paper from said peripheral tape.

2. The device of claim 1 wherein said support means further provides a housing supporting said solenoid means, the upper surface of said housing being said supporting surface, and further comprising a member of sheet material mounted above said supporting surface and defining therewith a slot for receiving said card, said member also defining an aperture in general register with said aperture of said supporting surface for permitting reciprocation of said plunger.

3. The device of claim 2 further comprising a receptacle insertable in said housing and located beneath said aperture for receiving waxed papers removed from said cards.

4. The device of claim 3 wherein said solenoid means includes an armature spring-biased in said first position to fully reciprocate from said first position to said second position and back to said first position when energized and when said card is removed.
